BANJO HEAD

Filed May 4, 1926

UNITED STATES PATENT OFFICE

WILLIAM L. LANGE, OF NEW YORK, N. Y.

BANJO HEAD

Application filed May 4, 1926. Serial No. 106,669.

My present invention relates to an improvement in musical instruments, and more especially relates to banjos, and has for its principal object an improvement in the structural features of the banjo body proper.

One of the features of the present invention is the making of the body of the banjo consisting of the rim, the head and a resonator attached to the rim all of wood and permanently jointed together.

Another feature of the invention relates to the manner in which the resonator is constructed and the means whereby the musical resonance of the instrument is conducted from the interior of the instrument to the atmosphere and is controlled in the direction of its emission.

Another feature is the utilization of a wooden head, constituting a sounding board, as a substitute for the vellum heretofore used, and the means for supporting the wooden head and sustaining the strain or stress of the strings.

An important advantage of my construction is the use of an all wood body whereby the musical qualities of the banjo are increased and the characteristic tone of the familiar type of banjo is obviated.

Other objects of the invention will appear as the description proceeds, and while herein details of the invention are described the invention is not limited to these, since many and various changes may be made without departing from the spirit of the invention or exceeding the scope of the appended claims.

Referring to the accompanying drawings,

Fig. 1 is a side elevation of my device in fragmentary section a portion of which is taken on the line 2-2 of Fig. 2,

Fig. 2 is a plan view,

Fig. 3 is a sectional view of a modified form,

Fig. 4 is a section on the line 4-4 of Fig. 1, and

Fig. 5 is a fragmentary sectional view of the resonator shown in Fig. 1.

Similar reference characters denote similar parts throughout the several views.

The present banjo is of all wood construction as relates to the instrumental or body

portion and comprises the rim 1 having thereon the outwardly convexed head 2 which on its under side at its circumferential margin bears on the top of the rim 1 and is permanently secured thereto as by gluing. The head 2 has on its under side the supporting cross-pieces 3 curved on their top edges to conform to the concavity of the under side of the head 2 and which are cut away at their ends 4 for engagement with insets 5 at the top of the rim, the cross-pieces 3 being reduced in thickness towards their bottom edges as shown in Fig. 4 for conducting to the resonant quality.

The resonator R is arranged at the bottom of the rim 1 and consists of the outer annular wall 6, the outwardly convexed back 7 and the inner annular wall 8, all of wood and permanently secured together as by gluing. The outer wall 6 is spaced away laterally from the bottom end of the rim 1 and is secured thereto by the top piece or facing 9 which engages at its inner marginal portion the rabbet 10 of the rim. The top piece 9 is provided with the series of sound emitting openings 11. The back 7 is secured at its circumferential edge to the bottom of the wall 6. The inner wall 8 is of less diameter than the outer wall 6 and its top bears against and is secured to the under side of the inner margin of the top piece 9 adjacent to the bottom edge of the rim 1 and at its bottom bears upon and is secured to the inner side of the back 7, the resonating chamber 12 being formed between the outer and inner annular walls 6 and 8. The inner wall 8 is provided with the series of openings 13 communicating between the interior of the banjo and the resonating chamber 12. The strings 14 are stretched over the head 2 in the usual manner, being supported by the bridge 15 which preferably is placed over or near one of the cross-pieces 3, the cross piece 3 thus supporting the head against the pressure of the strings on the bridge and head when the strings are under tension.

Referring to Fig. 3, the inner annular wall of the modified form of resonator consists of a series of spaced legs 16 formed on the bottom of the rim 1 and bearing at their bot-

tom ends on the back 7 and having between the legs the openings 17 which provide communication between the interior of the banjo and the resonating chamber 12.

5 In use of the banjo the sound waves from the interior of the instrument pass through the openings 13 or 17 as the case may be into the resonating chamber 12 and are emitted through the openings 11 to the atmosphere 10 in direction away from the player and away from his body and towards the hearers, the rim, head and resonator all being of wood and joined together to provide a banjo body of permanently joined parts having the 15 resonance peculiar to instruments of all wood parts and free from the tone characteristics of the familiar type of banjos.

What I claim and desire to protect by Letters Patent is:

20 1. In a stringed musical instrument, in combination, a rim, a head on one end of said rim, and a resonator on the opposite end of the rim, said resonator including an outer side wall disposed in a plane parallel to and outwardly of the plane of the rim and an inner side wall parallel to the outer side wall and spaced away inwardly from the outer side wall and providing a resonating chamber between said walls, and a sounding board, said 25 sounding board providing bottom closure for said chamber and bottom closure for the space enclosed by said inner side wall, said space communicating with the interior space of the rim, said inner side wall having means 30 for passage of sound into the resonating chamber from said interior space of the rim and from said space enclosed by said inner side wall.

2. In a stringed musical instrument, in 40 combination, a rim, a head on one end of said rim, and a resonator on the opposite end of the rim, said resonator including an outer side wall disposed in a plane parallel to and outwardly of the plane of the rim and an inner side wall parallel to the outer side wall and spaced away inwardly from the outer side wall and providing a resonating chamber between said walls, and a sounding board, said sounding board providing bottom closure 45 for said chamber and bottom closure for the space enclosed by said inner side wall, said space communicating with the interior space of the rim, said inner side wall having means for passage of sound into the resonating chamber from said interior space of the rim and from said space enclosed by said inner side wall, said rim, head, outer and inner side walls and sounding board being of the same resonating material.

60 3. In a stringed musical instrument, in combination, a rim, a head on one end of said rim, and a resonator on the opposite end of the rim, said resonator including an outer side wall disposed in a plane parallel 65 to and outwardly of the plane of the rim and

an inner side wall parallel to the outer side wall and spaced away inwardly from the outer side wall and providing a resonating chamber between said walls, a top closure with openings therefor for passage of sound from said chamber, and a sounding board, said sounding board providing bottom closure for said chamber and bottom closure for the space enclosed by said inner side wall, said space communicating with the interior space of the rim, said inner side wall having openings therein for passage of sound into the resonating chamber from said interior space of the rim and from said space enclosed by said inner side wall.

4. In a stringed musical instrument, in combination, a rim, a head on one end of said rim, and a resonator on the opposite end of the rim, said resonator including an outer side wall disposed in a plane parallel to and outwardly of the plane of the rim and an inner side wall parallel to the outer side wall and spaced away inwardly from the outer side wall and providing a resonating chamber between said walls, and a sounding board, said sounding board providing bottom closure for said chamber and bottom closure for the space enclosed by said inner side wall, said space communicating with the interior space of the rim, said inner side wall having openings therein for passage of sound into the resonating chamber from said interior space of the rim and from said space enclosed by the inner side wall, said head being outwardly convexed and said sounding board being outwardly convexed in direction opposite to the convexity of the head.

5. In a stringed musical instrument, in combination, an annular rim, a circular head on one end of said rim, and a resonator on the opposite end of the rim, said resonator including an annular outer side wall disposed in a plane parallel to and outwardly of the plane of the rim and an annular inner side wall parallel to the outer side wall and spaced away inwardly from the outer side wall and providing an annular resonating chamber between said walls, and a circular sounding board, said sounding board providing bottom closure for said chamber and bottom closure for the space enclosed by said inner side wall, said space communicating with the interior space of the rim, said inner side wall having openings therein for passage of sound into the resonating chamber from said interior space of the rim and from said space enclosed by the inner side wall, said head having a convexity which is the same arc of a circle from the center of the head to all points on the circumference of the head, said sounding board having a convexity in direction opposite to the convexity of the head and which is the same arc of a circle from the center of the sounding board to all points on the circumference thereof.

6. In a stringed musical instrument, in combination, a rim, a head secured at its margin to one end of said rim, an outer side wall disposed in a plane parallel to and outwardly of the outer side of the rim and supported by the end of the rim opposite to the first mentioned end, an inner side wall disposed parallel to the plane of the outer side wall inwardly of the outer side wall and supported by the same end of the rim that supports the outer side wall and forming with the outer side wall a resonating chamber, said inner side wall having openings therethrough for passage of sound from the interior chamber space of the instrument into the resonating chamber, and a sounding board providing bottom closure for the resonating chamber and back closure for the interior chamber space of the instrument. 10
- 15 7. In a stringed musical instrument, in combination, a rim, a head secured at its margin to one end of said rim, an outer side wall disposed in a plane parallel to and outwardly of the outer side of the rim, an inner side wall disposed parallel to the plane of the outer side wall inwardly of the outer side wall and forming with the outer side wall a resonating chamber, closure means for the top of the resonating chamber and serving to support 20 said outer and inner side walls on the end of the rim opposite the first mentioned end, said top closure means having openings therethrough for passage of sound from the resonating chamber, said inner side wall having 25 openings therethrough for passage of sound from the interior chamber space of the instrument into the resonating chamber, and a sounding board providing bottom closure for the resonating chamber and back closure for 30 the interior chamber space of the instrument. 35
- 40 8. In a stringed musical instrument, in combination, a rim, a pair of supports spaced apart and disposed transversely of the rim relative to the line of the strings of the instrument and secured at their ends on the rim, and a head secured at its margin on the rim and bearing at its under surface on said supports and supported thereby inwardly of its margin in the longitudinal line of the supports, said rim, head and supports being composed of the same resonating material. 45
- 50 9. In a stringed musical instrument, in combination, a rim, a pair of supports spaced apart and disposed transversely of the rim relative to the line of the strings of the instrument and secured at their ends on the rim, a head secured at its margin on the rim and bearing at its under surface on said supports and supported thereby inwardly of its margin in the longitudinal line of the supports, and a bridge disposed on the outer surface of said head in the longitudinal line of one of said supports whereby said support reinforces the head for sustaining the pressure of the strings on the bridge, said rim, 55 60 65
- head and supports being composed of the same resonating material. 70
- 75 10. In a stringed musical instrument, in combination, a rim, a pair of supports spaced apart and disposed transversely of the rim relative to the line of the strings of the instrument and secured at their ends on the rim, and a head secured at its margin on the rim and bearing at its under surface on said supports and supported thereby inwardly of its margin in the longitudinal line of the supports, said head being outwardly convexed and said supports being curved on their head supporting edges for conforming to the concavity of the head on its side opposite said 80 85 90 95 100 105 110 115 120 125 130 convexity. 11. In a stringed musical instrument, in combination, a rim, having a rabbet on the inner side of one of its ends, a pair of supports spaced apart and disposed transversely of the rim relative to the line of the strings of the instrument and secured at their ends on said rabbet, a head secured at its margin on the rim and bearing at its under surface on and secured to said supports and supported thereby inwardly of its margin in the longitudinal line of the supports, said head being outwardly convexed and said supports being curved on their head supporting edges for conforming to the concavity of the head on its side opposite said convexity, and a bridge exposed on the outer surface of said head in the longitudinal line of one of said supports whereby said support reinforces the head from sustaining the pressure of the strings on the bridge. 12. In a stringed musical instrument, in combination, a rim, a head on one end of said rim, an annular wall concentric with said rim, an annular member provided with openings in contact with said rim and wall, a second annular wall provided with apertures concentric with said first wall, and a back member in contact with said first and second walls. 13. In a stringed musical instrument, as defined in claim 12, said head and back member being outwardly convexed in opposite directions.

Signed at New York in the county of New York and State of New York this 3rd day of May A. D. 1926.
